UNITED STATES PATENT OFFICE.

PHILIP M. ENGLISH, OF BAYONNE, NEW JERSEY; ADA J. ENGLISH EXECUTRIX OF
SAID PHILIP M. ENGLISH, DECEASED.

FLUSH-TANK VALVE AND APPURTENANCES.

1,348,790.

Specification of Letters Patent.

Patented Aug. 3, 1920.

Application filed February 16, 1918. Serial No. 217,690.

To all whom it may concern:

Be it known that I, PHILIP M. ENGLISH, a citizen of the United States, and a resident of Bayonne, in the county of Hudson and State of New Jersey, have invented certain new and useful Improvements in Flush-Tank Valves and Appurtenances, of which the following is a specification.

This invention relates to a flush tank valve and appurtenances. It is characterized by a non-collapsible float, the buoyancy of which coacts with the operations of the valve.

In the accompanying drawings, Figure 1 represents an elevation and part section of the improved flush tank valve with its tank, as on the line 1, 1 of Fig. 2, and Fig. 2 shows a top plan view of Fig. 1 when not sectioned, and its cover removed.

20 A tank is shown with the bottom 20, front wall 22, rear wall 23 and end walls 24 and 25. A detachable cover 26 is provided for the tank. The usual inlet valve 28 extends up from the bottom 20. The latter is actuated by the float 29, and has leading thereto the inlet piping 30. A threaded sleeve 31 has formed at its upper end the cap with the flanges 32 and 33. The upper face of the flange 32 constitutes a valve seat 34. An extension 35 with the cavity 35^a is formed with said cap. An elongated guide 36 coaxial with the sleeve 31 is connected to the latter by the arms 37. A packing ring 38 is located between the bottom face of the flange 33 and the top face of the bottom 20. A clamping nut 39 is in threaded engagement with the sleeve 31 and bears against the packing ring 40, which latter in turn bears against the bottom face of the bottom 20 of the tank. Outlet piping 44 is connected to the sleeve 31. A hollow column 45 with the slots 46 at its upper end, extends up from the extension 35. The interior of the said column leads to cavity 35^a. An oscillating beam comprises the barrel 47 with the caps 48 and 49 in threaded engagement with the ends thereof. A flange 50 extends from the barrel 47 parallel to the longitudinal axis thereof and is located in the slots 46. A hinge pin 51 extends through the column 45 and supports the flange 50. A counter-balancing ball 52 is located in the barrel 47 and can freely roll therein. A rigid valve stem 56 is slotted at its upper end and the flange 50 extends into

said slot. A pin 57 connects the stem 56 and the flange 50. The opening in the flange 50 for the pin 57 is elongated to enable the flange 50 to oscillate without bending the rigid valve stem 56. The lower end 60 of the valve stem 56 is guided in the elongated guide 36. A disk flush valve is indicated at 60, above which is located a non-collapsible float 61 of buoyant material like cork.

65 A washer 62 bears on the float 61 and a nut 63 in threaded engagement with the valve stem 56 bears on the washer 62. A washer 64 bears up against the valve 60 and a nut 65 is in threaded engagement with the 70 valve stem 56, and bears against the washer 64. An operating bar 70 extends from the cap 49. A tipping device comprises a bracket 71 from which extends a threaded sleeve 72 and the stop pins 73 and 74, which 75 extend through the front wall 22 of the tank. A nut 76 with the extension 77 is in threaded engagement with the sleeve 72 and bears against the front face of the wall 22. A pivot 79 with its rear end 80 squared, is 80 supported in the sleeve 72. A tipping bell crank with the arms 82 and 83 is pivoted on the bracket 71 by means of the pivot pin 84. A pair of links 85 have each one end pinned to the arm 83 by means of the pin 86. The 85 other end of the links 85 is pinned to a crank 89 by means of the pin 90. The other end of the crank 89 is supported on the squared end 80 of the pivot 79. An operating handle 92 is fastened to the pivot 79. The arm 82 is located to clear the bar 70 when in its neutral position, when the barrel 47 is tipped forwardly as indicated in the drawings and the valve 60 located on its seat 34.

90 The operation of the invention is as follows: The inlet valve 28 operates in the usual manner and need not be described. To operate the flush disk valve 60 to discharge water through the piping 44, the operator swings the operating handle 92 100 in either direction, and thereby the link 89 swings until it bears against one of the stop pins 73 or 74. This causes the arm 82 to bear up against the operating bar 70 and tips the barrel 47 in the direction of the 105 arrow A, raises the flush valve 60 from the valve seat 34, and also raises the float 61. At the same time the ball 52 which is bearing against the cap 49 rolls to the other end of the barrel 47 and bears against the 110

cap 48. The flush valve 60 uncovers the opening through the sleeve 31 until the water in the tank lower to a predetermined level as indicated by the line B, B. The size of the float 61 is proportioned so that when the water lowers to the level of the line B, B, the upper portion of the float 61 will not be submerged, and it will sink and tip the barrel 47 in a direction opposite to the arrow A. The ball 52 rolls to bear against the cap 49 and the flush valve 60 will be seated on its seat 34, thereby closing the opening or port through the sleeve 31. The buoyancy of the non-collapsible float 61 keeps the valve 60 off of its seat while it is submerged, and closes said valve when the water lowers sufficiently not to completely submerge said float. The ball 52 performs the functions of a counterbalance and assists by reason of its weight in maintaining the valve 60 in either its closed or open position. When the valve 60 is in its closed position and the water rises to the top edge of the hollow column 45, the water will flow through the said column, the cavity 35^a and be discharged through the sleeve 31. The column 45 with the cavity 35^a constitutes an overflow for the tank.

Having described my invention, what I desire to secure by Letters Patent and claim is:

1. The combination of a tank, a sleeve extending through the bottom of the tank, the upper face of the sleeve constituting a valve seat, the sleeve having an extension 35 with a cavity that leads to the opening through the sleeve, means to secure the sleeve in place to the bottom of the tank, a hollow column with slots at its upper end supported on said extension with its interior in connection with said cavity, an oscillating beam comprising a barrel with a flange parallel to the longitudinal axis thereof, the said flange located in the slots in the upper end of said hollow column, a hinge pin extending through the column and the flange of the barrel to allow the latter to oscillate, a counter-balancing ball in the barrel, a

rigid valve stem with one end pinned to the flange of the barrel, a valve and a non-collapsible float secured to the other end 50 of the valve stem coaxing with said valve seat, an arm to tip the beam and an operating handle to actuate the arm.

2. The combination of a tank, a sleeve extending through the bottom of the tank, 55 the upper edge of the sleeve constituting a valve seat, said sleeve having an extension with a cavity connecting with the interior of the sleeve, a hollow column supported on said extension, an oscillating beam having a flange, a hinge pin connecting said flange and hollow column, a counterbalancing ball in the barrel, a rigid valve stem with one end pinned to the flange, a valve and a non-collapsible float secured to the other end of the valve stem coaxial with 60 the valve seat an operating bar extending from one end of the barrel, a tipping device coaxing with the operating bar and comprising a bracket with a pair of stop pins and a sleeve, the said sleeve extending through the front wall of the tank, means to lock the latter sleeve in place, a pivot supported in the latter sleeve, a tipping bell crank with a pair of arms pivoted on said 65 bracket, a pair of links with one end of each pinned to one of the arms of the bell crank, a crank with one end pinned to the pair of links, the other end of the crank secured to said pivot, and coaxing with the stop pins of the bracket and an operating handle fastened to the pivot, the other arm of the bell crank coaxing with the operating bar to tip the oscillating beam with 70 the operating handle swung in one direction or in a reverse direction.

Signed at Bayonne, in the county of Hudson and State of New Jersey this 1st day of February, A. D. 1918.

PHILIP M. ENGLISH.
